DESIGN FOR A LACE FABRIC OR SIMILAR ARTICLE

Edward Clay, Bristol, R. I.

Application February 18, 1938, Serial No. 75,221

Term of patent 3½ years

To all whom it may concern:

Be it known that I, Edward Clay, a subject of the King of Great Britain, residing at Bristol, Rhode Island, have invented a new, original, and ornamental Design for a Lace Fabric or Similar Article, of which the following is a specification, reference being had to the accompanying drawing, forming a part thereof.

The figure is a plan view of a lace fabric, show-

ing my new design. The dot and dash lines on the drawing outline substantially a design unit, which unit is repeated in regular succession as indicated by the extensions beyond the unit boundaries.

I claim:

The ornamental design for a lace fabric or similar article as shown and described.

EDWARD CLAY.
